PADLOCK

Edward N. Jacobi, Milwaukee, Wis., assignor to
 Briggs & Stratton Corporation, Milwaukee,
 Wis., a corporation of Delaware

Application August 9, 1935, Serial No. 35,490

15 Claims. (Cl. 70—108)

This invention relates to improvements in padlocks and has as an object to provide an improved design and construction whereby the manufacture and particularly the assembly of the lock 5 are materially simplified to effect a saving both in labor and material.

More specifically it is an object of this invention to provide a padlock which is so constructed that the assembly of the component parts is effected 10 by merely snapping together the several parts which act as spring detents to retain each other thus obviating entirely the necessity for screws, pins or other holding devices.

A further object of this invention is to provide 15 a padlock structure wherein assembly and disassembly requires a predetermined position of rotation of the cylinder and in which one of the tumblers of the cylinder normally serves to prevent turning the cylinder to said position.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one 25 complete example of the physical embodiment of the invention constructed according to the best mode so far devised for the practical application of the principles thereof, and in which:

Figure 1 is a longitudinal section view through 30 a padlock embodying this invention and showing the same in its locked condition;

Figure 2 is a view similar to Figure 1 but in unlocked condition;

Figure 3 is a cross section view taken through 35 Figure 1 on the plane of the line 3—3;

Figure 4 is a cross section view taken through 40 Figure 2 on the plane of the line 4—4;

Figure 5 is a cross section view taken through Figure 1 on the plane of the line 5—5 with the 45 cover plate and bolt removed;

Figure 6 is a cross section view through Figure 1 on the plane of the line 6—6;

Figure 7 is a cross section view taken on the 50 plane of the line 5—5 of Figure 1; and

Figure 8 is a section view taken through Figure 5 on the plane of the line 8—8.

Referring now more particularly to the accompanying drawings in which like numerals indicate like parts throughout the several views, the numeral 5 designates the body of the padlock which

mounts a shackle 6 adapted to be secured in a closed or locked position by a locking bolt 7 controlled by a lock cylinder 8. The body 5 is preferably a die casting and has two bores 9 and 10 at one end at opposite sides of a central bore 11 in which the cylinder 8 is mounted. The bore 10 has the long leg 12 of the U-shaped shackle 6 disposed therein and the bore 9 is adapted to receive the short leg 13 thereof.

It is to be noted that the axis of the bore 11 10 and consequently the cylinder 8 does not lie in the plane passing through the centers of the bores 9 and 10, but is disposed to one side thereof. This off-center relationship between the axes of the shackle legs and the cylinder is utilized to 15 facilitate assembly of the lock, as will be herein-after more fully described.

At its end from which the shackle projects, the body 5 has transverse axially aligned bores 14 and 15 intersecting, respectively, with the bores 20 9 and 10 and communicating with the central bore 11. These transverse axially aligned bores 14 and 15 mount the locking bolt 7 and a bushing 16. The bushing 16 is disposed in the bore 15 which is of smaller diameter than the bore 25 14 and is held against outward movement by a flange 17.

The outer end of this bushing projects into the side of the bore 10 to retain the shackle bolt assembled with the body 5. To accommodate 30 the projecting end of the bushing, the long leg of the shackle is flattened as at 18, which results in a shoulder 19 at the lower end of the flattened portion 18. Engagement of this shoulder with the bushing 16 limits the outward projection of 35 the shackle bolt by its spring 20, and to permit turning of the bolt in the bore 10 after it has been projected to its open position, the leg 12 has a groove 21 formed therein with the shoulder 19 forming the lower edge thereof.

The bushing 16 is bored axially to receive the adjacent end 22 of the locking bolt, which as shown, is reduced in diameter to fit the bore in the bushing. The bushing thus serves to guide the adjacent end of the locking bolt and its flange 17 provides a spring stop against which one end of the bolt spring 23 abuts, the opposite end of the spring engaging a flange 24 on the bolt. The spring 23 yieldingly projects the bolt into the 50 bore 14 to engage its large diameter end 25 in a keeper recess 26 formed in the short leg 13 of the shackle. To retract the locking bolt out of the keeper recess 26, the lock cylinder 8 has an eccentric cam 27 projecting from its inner end 55.

to engage the flange 24 as long as the cylinder is within its normal limits of rotation.

- As is customary, the cylinder 8 has a plurality of key operable locking tumblers 28 yieldingly projectible into a longitudinal tumbler receiving groove 29 communicating with the bore 11 to normally hold the cylinder against rotation. The tumblers 28 are retractible to free the cylinder for rotation by the insertion of a proper key 30.
- 10 The innermost tumbler 31 is not acted upon by the key nor does this tumbler join with the others in holding the cylinder against rotation. Its function is to provide simple means for defining the normal limits of rotation of the cylinder. For this purpose, its projecting end portion is disposed in an arcuate chamber 32 forming substantially a sidewise extension of the tumbler receiving groove. Longitudinally this arcuate chamber extends from a point opposite the 15 tumbler 31 to the end of the bore 11 which is closed by the cover plate 34, as best shown in Figure 8.

The cover plate is secured in a shallow counter-bore 35 by being pressed into place. Prior to 25 being pressed into place, the cover plate is bulged outwardly so that pressing the same flat secures the cover plate in position. To prevent crowding the mouths of the bores 9 and 10, the cover plate is relieved as at 36 at the points opposite the 30 bores 9 and 10.

In assembling the lock, the cylinder is pushed into the bore 11 (before the cover plate 34 is in place) until a shoulder 37 at its lower end engages a flange 38 projecting from the wall of the 35 bore 11. Endwise movement of the cylinder in the direction of its insertion is thus limited by the shoulder 37 engaging the flange 38, and in the opposite direction, it is limited by the locking bolt.

40 To facilitate insertion of the cylinder, the mouth of the bore 11 has an inclined guideway 39 (see Figure 8) which serves to automatically depress the tumblers. This inclined guideway is so located that with the cylinder turned to align 45 the projecting ends of the tumblers therewith, the cylinder is in a position of rotation at which its eccentric driving cam is farthest from the plane passing through the axes of the bores 9, 10, 14 and 15 (see Figure 5). In other words, 50 in this position, the cam is turned aside so as not to interfere with the insertion of the locking bolt.

With the cylinder in this position, the bolt 7, its spring and guide bushing 16 are next inserted into the body through the bore 14, but before the 55 locking bolt is pushed all the way in to cause the guide bushing 16 to project into the bore 10, the shackle and its spring 20 are inserted into the bore 10. Then with the shackle held in, the locking bolt is pushed farther into the body by 60 means of a tool inserted through the open end of the bore 14 which causes the guiding and retaining bushing 16 to project into operative relationship with the shackle to hold the same in the body. The cylinder is then turned so that its 65 eccentric driving cam engages the flange 24 of the locking bolt and limits outward projection of the bolt by its spring and holds the bolt in place.

As will be readily apparent, as the cylinder is turned from its initial position, its innermost 70 tumbler 31 snaps into the arcuate chamber 32 and prevents rotating the cylinder back to a position at which the eccentric driving cam 27 is disengaged from the flange 24 on the locking bolt.

75 The assembly is then complete except for the

closing of the bore 11 by securing the cover plate 34 in position, which requires but a simple punch press operation.

From the foregoing description taken in connection with the accompanying drawings, it will be readily apparent to those skilled in the art to which this invention appertains, that this invention provides a padlock of simple and inexpensive construction and that the assembly of the lock is exceptionally rapid and free from 10 expensive operations as it consists only in snapping together the various parts which act as spring detents to retain each other in position, and in the single punch press operation for securing the cover 34 in place. There are no assembling operations of driving screws, pins, or similar fastening devices.

It will also be apparent that the small number of parts and the fact that each individual part can be made in a few simple operations by the 20 most efficient methods, further insures low cost of manufacture.

What I claim as my invention is:

1. In a padlock, the combination of a shackle, a locking bolt for securing the shackle closed, a 25 lock cylinder for retracting the locking bolt, a common housing having cavities to receive said elements, assembly of said parts with the body requiring the lock cylinder to be in a predetermined position of rotation during insertion of 30 the lock cylinder into the body and the turning of the cylinder from said position, and means for preventing retrograde rotation of the lock cylinder to said predetermined position.

2. In a padlock, the combination of a body having a plurality of open ended substantially parallel bores connected near their mouths by a cross bore, a U-shaped shackle having its legs receivable in two of said parallel bores, a lock cylinder in another of said parallel bores between the 40 legs of the shackle, a locking bolt movable in the cross bore to and from a position engaging one of the legs of the shackle to lock the same closed, said locking bolt extending across the end of the cylinder to hold the same in its bore, an eccentric 45 cam on the cylinder to engage the locking bolt whereby rotation of the cylinder retracts the bolt, said eccentric cam being disengaged from the locking bolt when the cylinder is in a predetermined position of rotation so that assembly 50 and disassembly of the locking bolt from the body is possible when the cylinder is in said position of rotation, and means for preventing rotation of the cylinder to said predetermined position, said means becoming operative upon turning of the cylinder to operatively engage the eccentric cam with the locking bolt.

3. In a padlock including a rotatable lock cylinder and a locking bolt, a body having open bores into which the bolt and cylinder are insertable 60 with the bolt in a position preventing removal of the cylinder, and an operative driving connection between the cylinder and the bolt, said connection being established by rotation of the cylinder, and said connection preventing removal 65 of the bolt from said body.

4. In a padlock, the combination of a body having spaced parallel bores and having a central bore disposed therebetween with a transverse bore connecting the same with said parallel bores 70 near their open ends, a lock cylinder disposed in the central bore insertable and removable through the open end thereof, means at the opposite end of the central bore for holding the cylinder therein, a U-shaped shackle having its legs receivable 75

- in said spaced parallel bores at the sides of the lock cylinder, one of said legs being longer than the other, a spring engaging the long leg of the shackle for yieldingly urging the shackle outwardly to disengage its short leg from its bore, a locking bolt slidable in the transverse bore across the end of the lock cylinder to hold the lock cylinder in its bore and engageable with the short leg of the shackle to secure the shackle in closed position, a spring for the locking bolt, a spring retainer providing an abutment for the locking bolt spring and engageable with the long leg of the shackle to hold the same against displacement from its respective bore, an eccentric driving connection between the cylinder and the locking bolt adapted to retract the bolt out of engagement with the short leg of the shackle and to limit outward projection of the bolt so as to prevent disassembly thereof from the body, said driving connection being maintained as long as the cylinder is held from being turned to a predetermined position of rotation, and means for preventing rotation of the cylinder to said predetermined position.
5. In a padlock, the combination of a body having spaced parallel bores and having a central bore disposed therebetween with a transverse bore connecting the same with said parallel bores near their open ends, a lock cylinder disposed in the central bore insertable and removable through the open end thereof, means at the opposite end of the central bore for holding the cylinder therein, a U-shaped shackle having its legs receivable in said spaced parallel bores at the sides of the lock cylinder, one of said legs being longer than the other, a spring engaging the long leg of the shackle for yieldingly urging the shackle outwardly to disengage its short leg from its bore, a locking bolt slidable in the transverse bore across the end of the lock cylinder to hold the lock cylinder in its bore and engageable with the short leg of the shackle to secure the shackle in closed position, a spring for the locking bolt, a spring retainer providing an abutment for the locking bolt spring and engageable with the long leg of the shackle to hold the same against displacement from its respective bore, an eccentric driving connection between the cylinder and the locking bolt adapted to retract the bolt out of engagement with the short leg of the shackle and to limit outward projection of the bolt so as to prevent disassembly thereof from the body, said driving connection being maintained as long as the cylinder is held from being turned to a predetermined position of rotation, and means for preventing rotation of the cylinder to said predetermined position.
6. In a padlock, the combination of a body, a shackle having spaced parallel legs received in said body, a locking bolt movable in the body to and from operative engagement with one leg of the shackle to secure the shackle closed, a spring for the locking bolt yieldingly urging the same into operative engagement with said leg of the shackle, a spring retainer against which the locking bolt spring abuts, said spring retainer being engageable with the other leg of the shackle to hold the same against detachment from the body, and common means for retracting the locking bolt against the action of its spring and for preventing displacement of the locking bolt from the body.
7. In a padlock, the combination of a body having spaced parallel bores open at one end and a transverse bore intersecting the bores near their open ends, a shackle having long and short legs received in said spaced bores, a spring engaging the long leg and yieldingly urging the same outwardly of its bore, a locking bolt slidable in the transverse bore with one end thereof engageable with a keeper recess in the short leg of the shackle to hold the shackle in locked position, a spring yieldingly urging the locking bolt toward the bore receiving the short leg of the shackle and outwardly through the open end of the transverse bore when the short leg of the shackle is not in place to be engaged thereby, a spring retainer against which the locking bolt spring abuts disposed in said transverse bore and projecting into the bore in which the long leg of the shackle is received for engagement with an abutment on said long leg of the shackle to prevent separation of the shackle from the body, and a driver within the body and engaged with said locking bolt for retracting the same out of locking engagement with the short leg of the shackle and for limiting its spring actuated movement so as to hold the locking bolt in the body.
8. In a padlock, the combination of a body having spaced parallel bores open at one end and having a transverse bore intersecting the spaced parallel bores near their open ends, a shackle having spaced legs received in said parallel bores, one of said legs being longer than the other whereby the short leg may be removed from its bore while the long leg remains in its respective bore, a spring engaging the long leg of the shackle to project the same outwardly from the body, a locking bolt slidable in the transverse bore to engage one end in a keeper recess in the short leg of the shackle, spring means yieldingly urging the locking bolt into the bore in which the short leg of the shackle is received for engagement in said keeper recess, said spring means also yieldingly urging the locking bolt out of the transverse bore when the short leg of the shackle is not in place to be engaged thereby, means for limiting the outward projection of the shackle by its spring, and key controlled means mounted within the body and drivingly connected with the locking bolt for retracting the locking bolt out of locking engagement with the short leg of the shackle and for limiting the spring pressed movement of the bolt to prevent detachment thereof from the body.
9. In a padlock, the combination of a body having spaced parallel bores at opposite sides of a central well and having a transverse bore intersecting said parallel bores and the well to communicate the same, a shackle having its legs received in the spaced parallel bores, one of said legs being longer than the other whereby the short leg is removable from its bore while the long leg remains assembled with the body, a locking bolt slidable in the transverse bore with one end engageable in a keeper recess in the short leg, a spring to yieldingly project the locking bolt into the bore in which the short leg of the shackle is received and for urging the locking bolt out of the transverse bore when the short leg of the shackle is not in place to be engaged thereby, a key controlled lock cylinder disposed in the well under the locking bolt to be held in place thereby, and an eccentric driving cam on the cylinder engageable with the locking bolt and for limiting outward projection of the bolt by its spring.
10. In a padlock, the combination of a body having spaced parallel bores at opposite sides of a central well and having a transverse bore in-

tersecting said parallel bores and the well to communicate the same, a shackle having its legs received in the spaced parallel bores, one of said legs being longer than the other whereby the 5 short leg is removable from its bore while the long leg remains assembled with the body, a locking bolt slideable in the transverse bore with one end engageable in a keeper recess in the short leg, a spring to yieldingly project the locking bolt 10 into the bore in which the short leg of the shackle is received and for urging the locking bolt out of the transverse bore when the short leg of the shackle is not in place to be engaged thereby, a key controlled lock cylinder disposed in the well 15 under the locking bolt to be held in place thereby, an eccentric driving cam on the cylinder engageable with the locking bolt and for limiting outward projection of the bolt by its spring, said driving engagement between the eccentric cam 20 and the locking bolt being maintained as long as the cylinder is held against being turned to a predetermined position of rotation, and means automatically operable upon proper assembly of the parts for preventing rotation of the cylinder 25 to said predetermined position.

11. In a padlock, a body, a shackle carried by the body, a locking bolt mounted in the body for axial movement to and from locking engagement with the shackle, a key operable lock cylinder 30 mounted in the body with its axis substantially perpendicular to the axis of the locking bolt, an eccentric driving cam on the lock cylinder engageable with the locking bolt for retracting the same out of locking engagement with the shackle, 35 the connection between the eccentric driving cam and the locking bolt being such that the locking bolt is held thereby against detachment from the lock body as long as the connection is maintained, and the axis of the lock cylinder being disposed 40 to one side of the axis of the locking bolt so that with the cylinder turned to a predetermined position of rotation the connection between the driving cam and the locking bolt is disabled, and means becoming operative during assembly of the 45 parts for holding the cylinder against turning to said position.

12. In a padlock, a body having a well opening to one end thereof and a transverse bore open at one end and communicating with the well near 50 the mouth thereof, a lock cylinder disposed in the well, a locking bolt slideable in the transverse bore across the adjacent end of the cylinder to hold the same in the well, a driving connection between the cylinder and the bolt, said driving connection en-

abling retraction of the bolt by turning of the cylinder and also holding the bolt in the transverse bore, and said connection being maintained only as long as the cylinder is held from being turned to a predetermined position of rotation, and means becoming operative during assembly of the parts for preventing rotation of the cylinder to said predetermined position. 5

13. In a padlock, a body having a well open at one end and a transverse bore open at one end 10 and communicating with the well near the mouth of the well, a shackle carried by the body and adapted to be locked thereto, a key controlled lock cylinder in the well, a locking bolt slideable in the transverse bore across the end of the lock 15 cylinder to hold the same in the well, a spring yieldingly urging the locking bolt into operative engagement with the shackle to secure the shackle in locked position, an eccentric driving cam on the lock cylinder engaging the locking bolt for 20 retracting the bolt out of locking engagement with the shackle upon rotation of the cylinder and for holding the locking bolt against removal from the transverse bore as long as the lock cylinder is held against being turned to a predetermined 25 position of rotation, and means becoming operative during assembly of the parts for preventing rotation of the cylinder to said predetermined position.

14. In a lock, a bored casing having an arcuate 30 chamber communicating with its bore, a lock cylinder rotatable therein, a plurality of key operable tumblers transversely slideable in the cylinder to and from locking engagement with the casing to secure the cylinder against rotation, said tumblers being retractible out of locking engagement with the casing by the insertion of the proper key into the cylinder, and an auxiliary tumbler similar in all respects to the key operable tumblers but inoperable by the key yieldingly 40 projected from the lock cylinder at all times into said arcuate chamber to be engaged with the ends thereof to limit rotation of the cylinder. 35

15. A padlock including a body, a shackle and a spring moved bolt to secure said shackle in 45 locked position by engaging a notch in the shackle, the shackle engaging portion of said bolt being cylindrical with a flat end, and the end of the shackle being tapered to cam the bolt against its spring by engaging the flat end of the bolt, 50 and means to limit the stroke of the spring moved bolt toward its locking position.

EDWARD N. JACOBI.
